2 SHEETS—SHEET 2.

UNITED STATES PATENT OFFICE.

DOUGLAS P. PARKER, OF SHREVEPORT, LOUISIANA.

KEROSENE-BURNING DEVICE.

1,316,736.

Specification of Letters Patent. Patented Sept. 23, 1915.

Application filed January 19, 1918. Serial No. 212,768.

To all whom it may concern:

Be it known that I, DOUGLAS P. PARKER, a citizen of the United States, residing at Shreveport, in the county of Caddo and 5 State of Louisiana, have invented a new and useful Kerosene-Burning Device, of which the following is a specification.

The structure forming the subject matter of this application is adapted for use with 10 internal combustion engines, and one object of the invention is to provide novel means whereby gasolene and a relatively heavy oil such as kerosene may be used interchangeably.

15 Another object of the invention is to provide novel means whereby the charge will be heated by the exhaust before the charge enters the intake manifold.

20 A further object of the invention is to provide novel means whereby water or steam may be introduced into the intake manifold when kerosene is used, the water or steam supply being cut off when gasolene is employed.

25 It is within the province of the disclosure to improve generally and to enhance the utility of devices of that type to which the present invention appertains.

With the above and other objects in view 30 which will appear as the description proceeds, the invention resides in the combination and arrangement of parts and in the details of construction hereinafter described and claimed, it being understood that 35 changes in the precise embodiment of the invention herein disclosed can be made within the scope of what is claimed without departing from the spirit of the invention.

In the accompanying drawings: 40 Figure 1 shows in side elevation, a device constructed in accordance with the present invention, parts appearing in section;

Fig. 2 is a vertical longitudinal section wherein parts appear in elevation;

45 Fig. 3 is a transverse section taken through the intake manifold and parts located therebelow; and

Fig. 4 is a fragmental cross section taken approximately on the line 4—4 of Fig. 1.

50 The numeral 1 denotes an exhaust manifold having an underlying tubular outlet 2 terminated in a flange 3. The manifold 1 is provided with the usual cylinder connections 4. At 5 there appears an intake manifold having cylinder connections 6. At its bottom, the intake manifold 5 is supplied

with a drum-like extension 7 including heads 8 and 9. Flues of relatively small diameter, denoted by the numeral 10, extend from the head 8 to the head 9, and open through the 60 heads.

The numeral 11 denotes, generally, a casing member, and the numeral 12 designates another casing member. The casing member 11 comprises a neck 14 and a cup-like body 15, 65 the body 15 being threaded on or otherwise secured to the head 8 of the extension 7. The neck 14 terminates in a flange 16 attached by means of securing elements 17 to the flange 3 of the outlet 2 for the exhaust manifold 1. The casing member 12 embodies a neck 18 and a cup-like body 19, the latter element being threaded upon or otherwise secured to the head 9 of the extension 7 of the intake manifold 5. At one end, the flues 75 10 open into the body 15, and at the other end, the flues open into the body 19. The neck 18 of the member 12 may terminate in an attaching flange 20.

A valve casing 21 is carried by the intake 80 manifold 5 intermediate the ends of the latter. A pipe 22 communicates with the valve casing 21 and is adapted to convey to the manifold 5, water or steam from any suitable source, such as the radiator of an 85 automobile. Journaled in the valve casing 21 is a one way valve 23 operated by means of an arm 24 pivoted at 25 to a screw 26 threaded into a sleeve 27, the sleeve being pivoted at 28 to a rider 29 held securely but 90 adjustably, by means of a set screw 30, to a controlling rod 31, pivoted at 32 to an extension 33 which may be prolonged to some point which will render this element accessible to an operator. 95

A valve casing 34 is connected by means of a neck 35 with the bottom portion of the drum-like extension 7 of the intake manifold 5, and opens between the heads 8 and 9. In the valve casing 34 is journaled a 100 three way valve 36, controlled by an arm 37 which is pivoted at 38 to the end of the rod 31.

The numeral 39 denotes a gasolene carbureter communicating with one end of the 105 valve casing 34, the numeral 40 marking a kerosene carbureter communicating with the other end of the valve casing, the three way valve 36 being located between the carbureters 39 and 40.

110 In practical operation, when the parts are arranged as shown in Fig. 1, kerosene vapor

supplied from the carbureter 40 will pass through the valve 36 and enter the intake manifold 5, through the drum-like extension 7. At the same time, water or steam will be admitted through the pipe 22 and the valve 23 into the intake manifold 5. When it is desired to use gasoline, the rod 31 is manipulated by means of the extension 33, a rotation being imparted to the valve 33 by the arm 34, the screw 26 and the sleeve 27, a rotation being imparted to the valve 26 by way of the rod 31 and the arm 37. When the valve 36 is rotated so that the gasoline carbureter 39 discharges into the intake manifold 5 through the drum-like extension 7, the valve 23 is rotated so as to cut off the supply of water or steam through the pipe 22. In view of the foregoing, it will be seen that water or steam will be supplied to the explosive mixture, when the basis of the explosive mixture is kerosene vapor: but, upon the other hand, no water will be supplied when the basis of the explosive mixture is gasoline vapor.

The valves 23 and 36 may be set to operate properly with respect to each other, and according to the procedure hereinbefore outlined, by threading the screw 26 into or out of the sleeve 27. Similarly, by shifting the rider 29 along the rod 31, and by holding the rider in adjusted positions through the medium of the set screw 30, the valves 23 and 36 may be set with respect to each other.

Ordinarily, the structure is started by the use of gasoline supplied from the carbureter 39, and when the engine has warmed up sufficiently, the gasoline carbureter 39 is cut off and the kerosene carbureter 40 is put into operation in the way hereinbefore described.

The exhaust proceeding from the manifold 1, traverses the outlet 2, the casing member

12, the flues 10, and the casing member 12. As the exhaust passes through the flues 10, the explosive mixture entering the intake manifold 5 by way of the drum-like extension 7 is heated, and the efficiency of the mixture is enhanced accordingly. 45

Having thus described the invention, what is claimed is:

In a device of the class described, an exhaust manifold; an intake manifold; carbureters communicating with the intake manifold; a two-way valve intermediate the carbureters and provided with a first arm, the valve constituting means for establishing communication between the carbureters, one at a time, and the intake manifold; a water supply conduit communicating with the intake manifold; a valve controlling the conduit and provided with a second arm; an operating rod pivoted to the first arm; a sleeve mounted to slide for adjustment along the rod; means for holding the sleeve in adjusted positions on the rod; a longitudinally adjustable connection comprising parts having their inner ends threaded together, one of said parts being pivoted to the sleeve; and a pivot element uniting the other of said parts with the second arm, the pivot element constituting means whereby the connection, as an entity, is movably assembled with the second arm, and constituting means for preventing relative movement between the parts of the connection thereby to maintain the connection at an adjusted length. 55 60 65 70 75

In testimony that I claim the foregoing as my own I have hereto affixed my signature in the presence of two witnesses.

DOUGLAS P. PARKER.
